UNITED STATES PATENT OFFICE.

WILLIAM WERNER, OF MEXIA, TEXAS.

MAGNETIC RECIPROCATING DEVICE.

Application filed August 14, 1926. Serial No. 129,276.

My invention relates to a magnetically operated means for reciprocating a load such as might be employed in pumping or other similar operations.

5 The invention is adapted to be employed in raising and lowering a mechanical device and is capable of application to many different uses. In the drawing, I have shown and described the device, however, as applied to a deep well pump.

It is an object of the invention to provide a means for raising and lowering a rod such as the pump rod and to so construct the device that its operation will be simple and 15 positive and in which the moving liquid being pumped will serve as a cooling means in the operation of the actuating device. It is desired to so construct the apparatus that it will withstand the heavy strains to 20 which it is subjected without danger of breaking or of overheating during the operation thereof.

The invention resides in the particular construction and arrangement of the parts 25 making up the apparatus and the points of novelty will be set out in greater detail in the claims appended hereto.

Referring to the drawing herewith, Fig. 1 is a central vertical section through the upper 30 end of the device embodying my invention. Fig. 2 is a similar view of the central portion of the device, and Fig. 3 is a similar section of the lower portion of the apparatus, it being understood that Figs. 1, 2 and 3 35 together show the complete apparatus with the parts in lowered position. Fig. 4 is a transverse section on the plane 4—4 of Fig. 7. Fig. 5 is a similar section taken on the line 5—5 of Fig. 7. Figs. 6 and 7 are upper 40 and lower longitudinal sections of the complete device showing the parts in raised position. Like numerals of reference are employed to designate like parts in all the views.

45 I have shown my device as seated in a well casing, indicated at 1. The device is housed within an outer tubular member 2 of a size to fit within the casing and having a loose contact therewith. The upper end of the 50 casing 2 is closed by a plug or nut 3 screwed in the upper end of said casing and having

a central opening threaded for engagement with the tubing 4 which extends upwardly from the casing to the surface to conduct away the fluid being pumped. The lower 55 end of the housing 2 is closed by a plug 3^a having a central opening within which is connected the lower section of tubing 4.

Within the housing 2 is fitted a casing 5 made up of a length of pipe of smaller diameter than the housing 2 and allowing at one side thereof a passage 6 for the fluid which is being pumped. The opposite side of the casing is adapted to contact with the inner wall of the housing 2. The upper 60 end of the casing has a plug 7 closing the same, said plug having an upwardly extending lug 8 at one side thereof to space the body of the plug from the lower end of the tubing 4, thus allowing free passage 65 of the fluid around the upper end of said plug. The lower end of the casing has a similar plug 7^a therein which is also spaced from the plug 3^a by means of a lug 8^a.

70 Within the casing 5 is placed an electro-magnetic core 9 which fills the interior of the casing at its upper end. The diameter of the core is decreased at a point somewhat below the upper end providing a recess indicated at 10 to receive the winding 11 of electrical conducting material. This winding 75 comprises a helix which is surrounded by a layer of insulating material 12. This winding extends downwardly around the core and somewhat beyond the cylindrical 80 portion thereof, as indicated clearly in the drawing. The lower end of the core 9 is tapered as shown at 13, coming to an apex 85 at a sharp angle somewhat below the lower end of the helix 11.

90 Within the core is formed a longitudinal channel or bore 14 extending the full length thereof and within this bore is a tube 15 of non-magnetic material. This tube has a head 16 at its upper end resting upon the upper face of the core 9 and extending slightly above said core. The lower end of the tube 15 is threaded within a stop head 17 which will be later described.

95 Within the tube 15 is a rod 19 having a head 20 thereon supported upon the upper end of the head 16 of non-magnetic mate-

rial. The rod 20 extends downwardly through the tube and is engaged within the stop head 17, previously referred to.

The tapered portion 13 of the core is 5 adapted to fit within the upper plate 21 of a series of interfitting armature plates. The plate 21 next adjacent the core is similar in general respect to each of the others. It has a plurality of vertical passages 22 extending therethrough and the lower end is connected with a cylindrical tube 23 which extends downwardly in contact with the non-magnetic sleeve 15, previously described. At its lower end it is threaded for engagement 10 within a bushing 24. Said bushing is a disc-shaped plate threaded on its outer periphery for engagement within a sleeve 25 extending downwardly from said bushing and connected at its lower end with an inner 15 ring or plug 26 which is beveled on its inner face to fit below the tapered shoulder 27 upon the stop head 17, previously referred to.

I have shown five armature plates similar 20 in construction to the plate 21. These plates may be designated 21, 21^b, 21^c, 21^d and 21^e. They are concentric and adapted to interfit with each other and the alternate plates, as 21^b and 21^d, have the lower tubes or sleeves 25^b and 25^d made of non-magnetic material so that there will be no tendency of the adjacent sleeves to adhere to each other due to the magnetic action of the central core. The bushings 24^b, 24^c, 24^d and 24^e are of increasing exterior diameter so that the sleeves 25^b, 25^c, 25^d and 25^e to which they are connected may fit closely, one against the other, and it will be noted that the alternate bushings and sleeves are of non-magnetic material for the purpose of preventing magnetic 30 action between the adjacent sleeves. A thin tube 27^a of non-magnetic material separates the outer sleeve 25^e from the casing 5 for the same purpose.

The stop head 7, previously referred to, is 35 tapered downwardly by stages, there being an upper cylindrical section 30 of predetermined length and a next lower cylindrical section 31 and between the cylindrical sections is a tapered surface 32. Below the cylindrical surface 31 is a third cylindrical surface 33, and below that is another cylindrical surface 34, and between the cylindrical surfaces are downwardly tapered shoulders 35, 36, and 37. Below the lower shoulder 37 the head is formed into a rod 38 which extends downwardly through a stuffing box 39 in the plug 7^a and downwardly into the lower tubing 4^a to be engaged with the pump 40 plunger, not shown. The upper end of the stop head 17 is formed with a plurality of 45 passages 40 which connect the space above the stop head with the space around the said head so as to allow the passage of the fluid therethrough in the operation of the device.

Each of the bushings 24^b, 24^c, and 24^d are 50 formed with longitudinal openings 42 therein connecting with an opening 43 in the outer tube 21^e so that the fluid may pass freely therethrough in order to facilitate the 70 operation of the device.

Each of the sleeves 25 is formed with horizontal slots therein to receive a pair of transverse pins 45. Said pins extend across 75 from one side of the housing 2 to the other, as shown particularly in Fig. 5. Slots are formed in each of the concentric sleeves 25 to allow the sliding of said sleeves for a limited distance therein, the rods 45 acting as a stop member to limit the downward 80 movement of the sleeves relative to the rods. In Figs. 2 and 7, dotted lines in said sleeves indicate the length of the slots. In Fig. 2 the pins are at the upper limits of the slots, and in Fig. 7 the pins are at the lower limits 85 of the slots.

The shoulders 32, 35, 36 and 37 upon the stop head serve to limit the upward movement of the sleeves relative to the head. To accomplish this, the lower ends of the sleeves 90 25 to 25^e inclusive are connected at their lower ends with plates 46, 47, 48 and 49 respectively, and it will be noted that the plates 46 and 48 are of non-magnetic material to correspond with the material in which 95 they are engaged. The said plates are formed with tapered recesses 50 centrally thereof to fit against the tapered shoulders formed on the stop head. These shoulders are spaced apart the proper distance so that 100 the shoulders engage with the recesses when the pump rod 38 is at the lower end of its stroke.

Between the casing 5 and the said plates 105 is a spacing member 51 which extends from the lower end of the winding 11 downwardly a predetermined distance and allowing the armature plates to move upwardly for a predetermined distance.

In the operation of the device it is to be 110 understood that the electric current may be operated by mechanical means to be turned on and off at predetermined intervals. When the current is turned on with the parts in the position shown in Figs. 1, 2 and 3, the core 9 will be energized and will attract the upper plate 21 drawing it into contact therewith. The plate 21 is then in effect a part of the core and the magnetic lines of force affect the next lower plate 21^a which is in turn drawn upwardly into contact with the plate 21. Each successive plate will thus be drawn upwardly until they are all nested together in contact with each other, as shown 115 in Figs. 6 and 7. When the plates are thus elevated they will through the sleeves 25 exert a lifting force upon the stop head 17. The ring 26 on the first sleeve will engage below the first shoulder 27, thus drawing the stop head upwardly with the sleeve. As the 120 125 130

next outer sleeve 25^a is elevated it will engage the plate 46 below the shoulder 32 and raise the stop head still further. When all the plates have been raised the stop head 17 will assume the position shown in Fig. 7, its upper end contacting with the cross rods 45 and the lower plate 49 only in contact with the head. When the current is again turned off the weight of the pump rod 38 10 with its load of liquid thereon will exert a force drawing the head with the armature plates above the same downwardly into the position shown in Figs. 1, 2 and 3. The fluid lifted by the pump will pass upwardly 15 through the tubing and through the channel 6 at the side of the casing 5 and between the same and the housing 2 and upwardly through the tubing to the surface. The interior of the casing 5 is understood as having lubricant therein which is circulated 20 through the passages 22, 40 and 43, thus tending to keep the parts cooled and also acting as a cushion to prevent the jars due to too rapid movement of the different parts 25 during the operation of the device.

It will be noted that the tapered surface of the core in connection with the tapered formation of the plates allows the movement of the plates through a longer distance before contact with the core is obtained and yet narrows the gap between the plates and the core so that the insulating effect of the air gap is greatly decreased. A superior lifting action is thereby obtained and a heavy load of liquid can be handled with a device of this kind with a current of ordinary intensity. The action of the pump is regular and positive and the device will not be subject to frequent repair as is usual in 40 pump operating means.

While I have shown the device as applied to a pump, it is obvious that it may be employed in reciprocating other parts than pump rods, and I do not wish, therefore, 45 to be limited to the exact construction set out.

Having thus described my invention, what I claim as new and desire to protect by Letters Patent is:

50 1. In a device of the character described, a casing, a magnetic core therein, a helix of electrical conducting material thereon, a load engaging rod extending through said core axially thereof, a stop head on said rod below said core, a series on concentric conical armature plates below said core adapted to extend within said helix, connections between said plates and said head, whereby the upward movement of said plates will 55 move said head and said rod.

60 2. In a device of the character described, a casing, a magnetic core therein, the lower end of which is tapered, a helix of electrical conducting material thereon, a load engag-

ing rod extending through said core axially 65 thereof, non-magnetic means separating said rod from said core, a stop head on said rod below said core, a series on concentric conical armature plates below said core and extending within said helix, connections between 70 said plates and said head, whereby the upward movement of said plates will move said head and said rod.

3. In a device of the character described, a casing, a magnetic core therein, a helix of 75 electrical conducting material thereon, a load engaging rod extending through said core axially thereof, a stop head on said rod below said core, a series on concentric conical armature plates below said core and partly 80 within said helix, connections between said plates and said head comprising sleeves secured to said plates and having a central enlarged chamber to receive said head and supporting plates below said head and 85 adapted to contact therewith, whereby the upward movement of said plates will move said head and said rod.

4. In a device of the character described, a casing, a magnetic core therein, a helix of 90 electrical conducting material thereon, a load engaging rod extending through said core axially thereof, a stop head on said rod below said core, a series on concentric conical armature plates below said core and partly 95 within said helix, connections between said plates and said head comprising sleeves secured to said plates and having a central enlarged chamber to receive said head and supporting plates below said head and 100 adapted to contact therewith, whereby the upward movement of said plates will move said head and said rod, each alternate sleeve and supporting plate being of non-magnetic material.

105 5. In a device of the character described, a casing, a core therein, a helix of electric conducting material thereon, the lower end of said core being tapered, a rod extending through an axial opening in said core, a stop head on said rod spaced below said core, armature plates of magnetic material and of conical formation below said core and extending within said helix, and means on said plates engaging beneath said stop head so 110 that when said plates are raised said head will also be elevated.

115 6. In a device of the character described, a casing, a core therein, a helix of electric conducting material thereon, the lower end of said core being tapered, a rod extending through an axial opening in said core, a downwardly tapered stop head on said rod spaced below said core, armature plates of magnetic material and of conical formation below said core extending within said helix, and means on said plates including bushings 120 having tapered recesses of varying diameter 125

therein engaging beneath said stop head, so that when said plates are raised said head will also be elevated.

7. In a device of the character described, a downwardly tapered core of magnetic material, a helix of conducting material around said core, conical shaped plates of magnetic material below said core extending within said helix, an axial rod extending through

said core and said plates, a stop head on said rod below said core, and sleeves on said plates about said rod having bushings engaging below said stop head, whereby said head and rod will be elevated when said plates are raised. 10 15

In testimony whereof I hereunto affix my signature this 10th day of Aug., A. D. 1926.

WILLIAM WERNER.
